UNITED STATES PATENT OFFICE.

WILLIAM H. ARBOGAST, OF DUNMORE, WEST VIRGINIA, ASSIGNOR TO WINFRED Mc-ELWEE, OF DUNMORE, WEST VIRGINIA.

WRENCH.

Application filed May 4, 1926. Serial No. 106,757.

The present invention appertains to improvements in wrenches, and particularly to that type known as pipe wrenches.

It has for its primary object to provide 5 a quick-adjusting action of the jaws and at the same time a powerful non-slipping gripping action by virtue of a peculiar clamping operation upon the shank of the movable jaw as pressure is applied to rotate the object engaged.

A further object in view is to provide a wrench, the parts of which may be readily assembled or disassembled as well as renewed in the event of breakage or wear.

15 Other objects and advantages of the invention will be hereinafter set forth and the novel features thereof defined by the appended claims.

In the accompanying drawings:

20 Figure 1 is a longitudinal sectional view of the preferred embodiment of this invention showing the wrench handle and coacting jaw in elevation;

25 Figure 2 is a transverse sectional view on the line 2—2 of Figure 1;

Figure 3 is a side elevation;

Figure 4 is a longitudinal sectional view of a modified form of the invention;

30 Figure 5 is a transverse sectional view on the line 5—5 of Figure 4; and

Figure 6 is a bottom plan view of the form of wrench shown in Figure 4.

Like reference characters designate corresponding parts throughout the several figures of the drawing.

Referring to the preferred form of my invention as disclosed in Figures 1 to 3, A designates the relatively movable jaw and B the relatively stationary jaw. The former 40 is composed of the jaw 1 proper, which is removably mounted through the instrumentality of the rivet 2 in the perforate extremity of the channel piece 3 which constitutes the shank of the jaw and a housing or guide 45 for the parts of the wrench construction, as will be more clearly apparent as this description proceeds.

The jaw B is formed at one side with a cylindrical boss or key-extension 4 which 50 freely fits in the correspondingly shaped socket or channel 5 in the end of the handle C, this connection of the jaw and handle being maintained by virtue of the cooperation of the surrounding sides of the channel 55 shaped shank 3. The jaw B obviously is

thus permitted to have a certain degree of rotation, relative movements of the handle and jaw being made possible. A spring 6 riveted to the band 7 at 8 bears against the jaw and tends to hold it against the base of 60 the shank channel.

This freedom of movement is particularly important in the preliminary adjustment of the jaws on the object to be gripped, the entrance to the jaw being enlarged by pressing the outer end of the jaw B against the object and thereby rotating it until abutment with the shoulder extremity 9 of the handle which acts to shift the jaw in the opposite direction upon rotation of the handle. Such rotation forces the jaw B firmly 70 against the object and the biting action becomes immediately effective.

In this form of the wrench the band 7 extends completely around the shank 3 and 75 the handle C and is provided with an aperture 10 receiving the boss 11 on the base of the handle. This interengagement constitutes an interlock which holds the parts of the wrench in assembled condition.

At one side the handle is provided with one way acting teeth 12 with which the spring actuated pawl 13 co-acts, said pawl having a depressible operating finger piece 14 positioned at the end of the shank 3 85 where it is readily accessible to the hand grasping the handle C. The pawl is pivotally mounted on the removable pin 13' passing through the sides of the shank 3.

The handle C is formed with the head 90 extension 15 which fits into the channel of the shank and cooperates with the boss thereof to produce a clamping action upon the shank which lies between said extension and the band, a very important feature of 95 this construction. That is to say, when the pressure is exerted against the handle for turning the object engaged, said handle rocks about the projection 11 until the extension 15 engages with the shank 3, forcing the latter against the band 7. Simultaneously, of course, the jaw B is forced into biting engagement with the object and the frictional clamping action just referred to increases in proportion to the amount of pressure exerted and the strain which would otherwise fall upon the pawl 13 is substantially entirely removed therefrom.

In general, the operation of the wrench is as follows: The pawl 13 being disengaged 105

from the rack teeth 12 by the thumb, the jaw A is shifted freely outwards until the proper opening of the jaws is obtained. With the jaw B held against the object, the 5 jaw A is now pressed back by the other hand until engaged with the object at the opposite side of the jaw B, the previously released pawl 13 sliding freely over the teeth 12 in this adjustment.

10 This is easily and quickly accomplished and then the handle C is rotated causing the extremity 9 to act against the jaw B and at the same time producing the clamping action on the shank 3 as hereinbefore 15 described.

The form of the device which is illustrated in Figures 4 to 6 differs slightly from the preferred embodiment but operates on exactly the same principles. The several 20 parts which correspond in these figures are therefore given the same reference numerals. In this form of the wrench I substitute for the band 7 a yoke 7' which is connected to a pin 16 passing through the inner end of 25 the jaw B' and the handle C being removably held by a cotter key 17. A flat leaf spring 18 secured to the handle C at 19 bears against the under edge of the jaw B' tending to force it into the position shown in 30 Figure 4, but permitting pivotal swinging movement of said jaw about the pin 16. At the top of the jaw an extension 20 is provided and extends into the channel shank piece 3 guiding the jaw in its pivotal movement. In this form of the device and in 35 the preferred embodiment, the head 15 of the handle C contacts with the shank piece where indicated by the arrow 21 to cause a clamping action of the shank against the 40 yoke 7'.

With respect to either of the wrenches hereinbefore described the jaw members may be easily removed whenever it is necessary to replace the same on account of breakage 45 or repair and the cost of such replacement would be nominal as compared with the replacement of the whole wrench as is required in most instances of present day constructions.

50 Having thus described my invention, what I claim as new and desire to secure by Letters Patent is:

1. In a wrench, a handle, a jaw member 55 swingingly connected thereto, a second jaw member having a channel-shaped shank in which to slidably receive the first jaw and handle, means adjacent the inner end of the handle to clampingly engage said shank, and means carried by the shank and engageable 60 with the handle to hold the jaws at adjusted position.

2. In a wrench, a handle having an abutment, a jaw member pivotally connected

thereto to swing into engagement with an abutment on the handle, a sliding jaw member, a yoke engaging about said jaw members and handle, and a pawl mounted on the sliding jaw member and engageable with the handle to hold the parts at adjusted position. 70

3. In a wrench, a handle, a jaw member connected thereto, a cooperating jaw member having a channel-shaped shank in which the handle and first mentioned jaw member are received, and a yoke member embracing the shank and movably connected to the handle to hold the parts assembled, said handle having means cooperative with the yoke to frictionally clamp the shank when the handle is rotated to impart gripping 80 action on the object engaged between the jaw members. 85

4. In a wrench, a handle, a jaw member mounted thereon, a second jaw member having a shank slideable relative to the first jaw and handle, means carried by the shank and engageable with the handle to hold the jaws at adjusted position, a member embracing the shank and handle and providing a pivot for the latter, and means adjacent 90 the inner end of the handle to clampingly engage said shank with said last named member. 95

5. In a wrench, a handle, a jaw member swingingly connected to the end thereof, a relatively movable jaw having a channel shaped shank, means embracing the shank and handle, means carried by said shank and engageable with the handle for holding the relatively movable jaw at adjusted position, and separate means operable by the handle for producing clamping action on the movable jaw shank. 100

6. In a wrench, a handle, a jaw member detachably connected thereto, a sliding jaw member having a channel-shaped shank engaging about the first mentioned jaw member and handle, a support embracing said shank and handle and providing a pivot for the latter, and latching means within the channel of the shank and engageable with the handle for holding the jaws at adjusted position. 105

7. In a wrench, a handle, a jaw having pivotal connection with the end thereof, a second jaw member having a shank extension, a yoke connecting said second jaw member with the handle, there being an extension upon the handle for clamping said shank and yoke in engagement, a locking pawl carried by the shank extension and engageable with the handle, and a spring coacting with the first mentioned jaw member. 115

In testimony whereof I affix my signature.
WILLIAM H. ARBOGAST.
